[57] CLAIM

The ornamental design for a high density DC-DC converter, as shown and described.

DESCRIPTION

FIGS. 1 and 2 are bottom and top vantage point isometric views showing my new design for a high density DC-DC converter;

FIG. 3 is a top plan view of the high density DC-DC converter of FIG. 1;

FIG. 4 is a side elevational view thereof, the opposite side being a mirror image of the high density DC-DC converter;

FIG. 5 is a bottom plan view thereof;

FIG. 6 is an end elevational view of the high density DC-DC converter; and,

FIG. 7 is an end elevational view thereof of the opposite side of the high density DC-DC converter of FIG. 6.
